UNITED STATES PATENT OFFICE.

WALTER M. DANN, OF WILKINSBURG, PENNSYLVANIA, ASSIGNOR TO WESTINGHOUSE ELECTRIC & MANUFACTURING COMPANY, A CORPORATION OF PENNSYLVANIA.

INDICATING DEVICE.

Application filed September 23, 1922. Serial No. 590,207.

My invention relates to indicating devices and it has particular relation to devices adapted to indicate the condition of a gas confined within a tank.

5 In the manufacture of tanks adapted to contain an oil-immersed electrical apparatus, such as transformers, oil circuit breakers and the like, it has been customary to provide breathing vents for the purpose of permitting 10 the oil within the tank to expand and contract with changes in the temperature thereof. Difficulty has been encountered with this type of apparatus for the reason that the oxygen contained in the air, which was admitted to 15 the interior of the tank through the breathing vent, combined with the oil and caused decomposition thereof.

The oxidation of the oil caused a viscous deposit or "sludge" that settled on the apparatus 20 and not only retarded the radiation of heat therefrom but seriously impaired the circulation of the oil through the cooling system thereof. Furthermore, if a short circuit or arc should develop in the submerged apparatus, 25 hydrogen and methane gases would be liberated from the insulating oil which would combine with the oxygen in the air within the tank to form a blanket of highly explosive gas over the insulating oil. In the event that 30 a spark should occur within the gas during a short circuit an explosion of considerable force would result, with consequent danger to life and property adjacent thereto.

In order, therefore, to reduce the above 35 mentioned hazard, it has been suggested to seal the interior of the tank from the outside atmosphere and to provide suitable means for permitting the expansion and contraction of the oil and to also replace the air contained in 40 the tank by an inert gas. This suggestion, while eliminating the danger from explosion, presented the difficulty of replacing the air by gas and constructing the tank with hermetically sealed seams to prevent the subsequent escape of the gas from the tank.

45 It has, therefore, been proposed to place within the tank a deoxidizing agent which is adapted to extract the oxygen from the air therein and leave a blanket of inert nitrogen 50 gas over the body of insulating oil which has no tendency to either cause the deterioration of the oil or to form an explosive mixture

when combined with the gases given off by the oil.

One of the objects of my invention is to 55 provide an indicating device by means of which the condition of the de-oxidizing agent may be visually ascertained in order that it may be replaced when completely oxidized without prematurely removing the cover from 60 the tank and permitting the escape of the inert gas that has been previously formed therein.

Another object of my invention is to provide a device, of the character described, 65 which is very simple in construction and operation and which may be mounted upon a tank without material changes in the structure thereof.

With such objects in view, as well as other advantages which may be incident to the utilization of the improvement, the invention 70 consists in the parts and combinations thereof hereinafter set forth and claimed, with the understanding that the several necessary elements constituting the same may be varied in 75 proportions and arrangement without departing from the nature and scope of the invention.

In order to make the invention more clearly understood, means are shown in the accompanying drawings for carrying the same into practical effect, without limiting the improvement, in their useful applications, to the particular construction which, for the purpose of explanation, are made the subject of illustration.

In the accompanying drawing:

Figure 1 is a vertical sectional view of the upper portion of a tank provided with an indicating device constructed in accordance 90 with my invention,

Fig. 2 is an enlarged view, partially in side elevation and partially in section, of another form of indicating device.

Referring to the drawing, a tank, adapted 95 to contain an oil-immersed electrical apparatus, is illustrated as comprising a body portion 1 and a cover 2 which is provided with the usual man-hole 3 and cover 4.

A receptacle 5, of any suitable construction, 100 is secured to the inner face of the cover 4 and extends downwardly into the upper portion of the tank.

When the tank is originally closed, a de-

oxidizing agent 6, such as phosphorus, is disposed within the receptacle 5 and in free contact with the air confined within the tank.

5 The de-oxidizing agent will soon absorb the oxygen contained in the air that is confined within the tank and leave an inert nitrogen gas over the insulating oil.

In order that the condition of the de-oxidizing agent contained in the receptacle 5 may 10 be quickly and easily ascertained without the necessity of removing the man-hole cover 4, or otherwise opening the tank, an indicating device 7 is provided on the tank. The device 15 7 preferably comprises a glass tube 8 which is suitably connected to the tank at its upper and lower extremities for communication with the interior thereof by means of pipes 9.

A suitable receptacle is mounted within the glass tube 8 in a position where it may be 20 conveniently observed and a replica 10 of the de-oxidizing agent is disposed therein. The proper size and proportions of the replica 10 relatively to the tube and to the main body of the deoxidizing material 6, indicates the degree 25 of deterioration of the two bodies, as their rates of change of appearance substantially correspond. The result is that the replica 10 becomes oxidized or otherwise deteriorates at substantially the same rate as 30 does the main body of de-oxidizing material 6 and the condition of that body may therefore be readily ascertained, as by optical inspection. Specimen 10 undergoes color changes, in addition to changes in its size.

35 In Fig. 2 is illustrated another form of the invention in which the tube 7 is mounted upon the cover of the tank. In this particular case, the tube 7 is secured, at its lower end, to the cover 2 of the tank by means of a nipple 11 and, at its upper end, by means of an 40 elbow 12, union 13 and pipe 14.

By means of the above-described constructions, a very simple and inexpensive indicating device is provided which may be easily 45 mounted on tanks of standard manufacture and which will accurately indicate the extent of the oxidation of the main body of de-oxidizing agent located within the tank.

I claim as my invention:

50 1. The combination with a tank having means for de-oxidizing the air contained therein, of a device for indicating the condition of said de-oxidizing means.

55 2. The combination with a tank adapted to contain a fluid immersed apparatus, of a de-oxidizing agent disposed within said tank and a device for indicating the condition of said agent.

60 3. The combination with a tank adapted to contain an oil-immersed electrical apparatus,

of a de-oxidizing agent disposed within said tank and a device for indicating the rate of deterioration of said agent.

4. The combination with a tank adapted to 65 contain an oil-immersed electrical apparatus, of a de-oxidizing agent disposed within said tank and a replica of said agent for indicating the condition thereof.

5. The combination with a tank adapted to 70 contain an oil-immersed electrical apparatus, of a de-oxidizing agent disposed within said tank and a replica of said agent mounted exterior to said tank and in contact with the gas contained therein for indicating the condition of said agent.

6. The combination with a tank adapted to 75 contain an oil-immersed electrical apparatus, of a de-oxidizing agent disposed within said tank, a glass tube mounted exteriorly of said tank and in communication therewith, and a replica of said agent disposed within said tube for indicating the condition of said agent.

7. The combination with a tank adapted to 80 contain an oil-immersed electrical apparatus, of a de-oxidizing agent disposed within said tank, a transparent housing carried by said tank and a replica of said agent disposed in said housing for indicating the rate of oxidization of said agent.

8. The combination with a tank adapted to 85 contain an oil-immersed electrical apparatus, of a de-oxidizing agent disposed within said tank, a housing carried by said tank and a replica of said agent visually disposed within said housing for indicating the condition of said agent.

9. The combination with a container having 90 therein a medium comprising a plurality of gases, of means for changing the relative proportions of said gases, and means controlled by said medium for indicating a condition of said first named means.

10. The combination with a container having 95 therein a medium comprising a plurality of gases, of means for changing the relative proportions of said gases, and means reacting with said medium for indicating a condition of said first named means.

11. The combination with a container having 100 therein a medium comprising a plurality of gases, of means for changing the relative proportions of said gases, and means controlled by said medium and disposed exteriorly of said container for indicating a 115 condition of said first named means.

In testimony whereof, I have hereunto subscribed my name this 15th day of September, 1922.

WALTER M. DANN.
